RELEASE VALVE

Frank A. Waterman, Norfolk, Va., assignor of
one-half to A. R. Thompson, Norfolk, Va.

Application January 25, 1939, Serial No. 252,840

1 Claim. (Cl. 137—21)

This invention relates to valves, and more particularly to release valves.

An object of the present invention is to provide a release valve for hot water tanks for automatically releasing the pressure in a hot water storage tank to prevent over-heating of the tank and exploding or bursting thereof; and the invention together with its objects and advantages will be best understood from a study of the following description taken in connection with the accompanying drawings wherein:

Figure 1 is a view illustrating somewhat diagrammatically the application of the invention.

Figure 2 is a top plan view of the valve, and Figure 3 is a vertical sectional view therethrough taken substantially on the line 3—3 of Figure 2.

Referring more in detail to the drawings it will be seen that the valve, in the preferred embodiment of the invention, comprises a casing indicated generally by the reference numeral 5.

Casing 5 is provided at one end thereof with a cold water inlet nipple 6 and at the opposite end thereof with a cold water outlet nipple 7. At the inlet 6 thereof the casing 5 is suitably connected with the cold water supply line 8 and at the cold water outlet end 7 thereof, the casing 5 is connected with the cold water pipe 9 that extends down into the hot water storage tank 10 through the top of the latter.

For the casing 5 there is also provided a dome 11 that at one end is provided with an apertured flange 12 through the medium of which and screws or other fastening elements 13 the dome 11 is secured to the flange 14 of a cylindrical neck 15 provided at the top of the casing 5 and at one end of said casing.

The dome 11 is provided with a lateral hot water inlet nipple 15 to which is connected the section of pipe 16 leading from a fitting 17.

The fitting 17 connects the hot water take-off pipe 18 with the hot water outlet 19 of the boiler 10 in the usual manner.

Also the dome 11 at the top thereof is provided with a hot water outlet nipple 20 to which is connected one end of a hot water overflow pipe 21.

At the inner end of the nipple 20 the dome 11 is provided with a valve seat 22 against which normally seats a suitable valve 23.

Valve 23 is provided on one end of a valve stem 24 that works through a suitable guide 25.

Guide 25 is in the form of a hub of a partition plate 26 the peripheral edge portion of which is clamped between the flanges 12 and 14 as shown in Figure 3.

Suitably mounted within the casing 5 adjacent to the cold water inlet end thereof is a thermostat 27 of any suitable design, and this thermostat 27 is suitably connected, as at 28, with the lower or free end of the valve stem 24.

As is well known the cold water from the source of supply enters the storage tank 10 through the pipe 9 and from the storage tank flows through the coil of a conventional hot water heater 29 back to the tank 10, the tank 10 being connected 10 with the inlet end of the coil of the heater 29 through the medium of a pipe 30, and with the outlet end of the coil of the heater 29 through the medium of the pipe 31.

With my invention applied as shown and described it will be apparent that as the water in the tank 10 becomes hot and expands and the water becomes overheated the hot water will back up through the cold water pipe 9 and the valve 5 and contact the thermostat 27. When this occurs the thermostat 27 will react in a manner to unseat the valve 23. The hot water flowing from the tank 10 through the pipe 18 will then also flow through the pipe 16 into the dome 11 by the open valve 23 and out through the outlet nipple 20 to be carried off by the overflow pipe 21. The escape of the hot water through the valve and the overflow pipe 21 will continue until cold water again enters the tank, coming into contact first with the thermostat 27 causing the latter to react to seat the valve 23 and thus cut off further escape of the hot water through the overflow pipe 21. Thus it will be seen that in actual practice the release valve of the invention will automatically open when necessary to relieve the storage tank of hot water and thereby prevent an explosion or bursting of the storage tank. With a release valve of this character used in the manner intended the use of a check valve in the cold water supply line to the storage tank 40 may be dispensed with, since with this invention hot water will be precluded from backing up through the cold water supply and, as usually happens under such conditions, damage the water meter.

It is thought that a clear understanding of an invention of this character will be had without a more detailed description.

Having thus described the invention what is claimed as new is:

Means for automatically releasing hot water from the top of a hot water tank having a cold water supply pipe extending through the top of the tank to a point adjacent the lower end thereof, said means comprising a casing superimposed

in the cold water pipe adjacent the point where the pipe enters the tank, whereby the water flows through the casing before entering the tank, a hot water service pipe leading from the tank, said 5 casing having an upwardly extending portion, a partition plate extending across the top of said upwardly extending portion, a dome having its lower end resting on the partition plate, means for connecting together the partition plate, the 10 lower end of the dome and said upwardly extending portion of the casing, said dome having a discharge opening in its top forming a valve seat, a vertically arranged tubular guide carried by the

partition plate, a valve stem passing through the guide and having a valve at its upper end for engaging the seat, a thermostat in the casing and having one end connected with the lower end of the valve stem, said thermostat when acted on by cold water holding the valve closed, and said thermostat opening the valve when acted upon by hot water backing up in the cold water pipe and means for connecting a side port through the dome with the hot water service pipe leading from the tank. 5 10

FRANK A. WATERMAN.
